UNITED STATES PATENT OFFICE.

THOMAS RONSTROM, OF CHICAGO, ILLINOIS.

MEANS FOR VESSEL PROPULSION.

No. 829,033.

Specification of Letters Patent.

Patented Aug. 21, 1906.

Application filed February 12, 1904. Serial No. 193,232.

To all whom it may concern:

Be it known that I, THOMAS RONSTROM, a subject of the King of Sweden and Norway, residing at Chicago, in the county of Cook 5 and State of Illinois, have invented new and useful Improvements in Means for Vessel Propulsion, of which the following is a specification, reference being had to the accompanying drawings, forming a part thereof.

10 The purpose of this invention is to provide an improved construction of a vessel to be propelled by motor and employing a screw-propeller or equivalent device.

15 It consists of the features of construction set out in the claims.

In the drawings, Figure 1 is a side elevation of a boat having my improvements. Fig. 2 is a section at the line 2 2 on Fig. 1. Fig. 3 is a section at the line 3 3 on Fig. 1. 20 Fig. 4 is a section at the line 4 4 on Fig. 1. Fig. 5 is a section at the line 5 5 on Fig. 1. Fig. 6 is a section at the line 6 6 on Fig. 4.

In my improved boat the propeller 1, in the customary form of a spiral blade or screw, 25 is located substantially midway in the length and width of the boat within a substantially cylindrical housing or waterway 2, the axis of the propeller and of said housing being horizontal and lying in a vertical longitudinal 30 mid-plane of the vessel. From each end of said horizontal housing or waterway two branches 3 3 lead divergently for a short distance to equal distances at opposite sides of said longitudinal mid-plane and then become 35 parallel and extend parallel with each other and with said mid-plane toward the bow and stern, emerging through the hull of the vessel as near together and as far from the bow and stern, respectively, as may be in view of the 40 contour of the vessel consistently with such emergence occurring as far below the water-line as possible and without deflection from a direct fore-and-aft course after said branches become parallel. This results in the mouth 45 of these ducts where they emerge through the hull being somewhat in the form shown in the side elevation, Fig. 1—that is to say, oval in oblique planes—on account of the hull being curved both longitudinally and 50 transversely at the point of such emergence. The propeller 1 has its shaft journaled in the ends of the cylindrical housing 2 at the junction or point of divergence of the two branches 3 3 at each end and is provided at 55 these points with suitable stuffing-boxes 5 5 to exclude the water from the interior of the

hull. Power may be applied to the shaft for rotating it by separate engines located one in each of the forks or intervals between the diverging branches 3 3. The details of means 60 for operating the shaft constitute no part of my invention and are shown only in the most limited conventional manner in the drawings.

In order to afford access to the propeller for repairs, the housing 2 is divided horizontally at the axis of the propeller, the upper portion constituting a cap which is removable to afford the access desired. This cap may be made in two or more sections, and these sections are arranged to be bolted together with packing to permit the junction to be water-tight, and the entire cap is secured to the lower half of the housing in similar manner.

In order to make it possible to remove the 75 cap of the propeller-housing while the vessel is in the water, gates 6 6 6 6 are provided, one at each of the branches 3 3 3, which may be closed to exclude the water before the cap is to be removed. The water remaining in the 80 housing will of course be exhausted by pump in any convenient manner. For the purpose of excluding ice from the water-passages 3 3 3 3 the mouths of these passages at the bow are provided with thin horizontal plates 8 8 85 8 8, constituting a grating by which large blocks of ice will be excluded, and even such as might be small enough to enter between the plates will be to some extent deflected and prevented from passing through the 90 passages and interfering with the action of the propeller. The plates are calculated to deflect the ice, as above suggested, by virtue of their horizontal position and outer edges, which are beveled or cut away to conform to 95 the outline of the hull, so that floating ice encountering the ends of the plates or drawn against them by the inflowing current of water will be guided along the sloping horizontal edges past the mouth. It will be obvious 100 that this result would not be obtained if the plates were vertical; but, on the contrary, vertical plates would tend to catch the ice and prevent even blocks too large to enter the mouth from gliding by the mouth, so 105 that the mouth might become obstructed by such blocks on account of the plates if the latter were vertical. These grating-plates may be removably secured in any practicable manner. When the boat is designed for 110 speed, this result may be better attained by reducing the discharge-aperture or emergence

of the water-passages at the stern to cause the jet of water which is discharged therethrough to receive a higher velocity at its emergence, and I have so illustrated said passages in the drawings. The extent of taper or reduction of the mouth of the passages may be greater or less, as desired, according to whether more or less power and less or more speed is to be attained.

10 I claim—

1. A vessel having a substantially cylindrical propeller housing or waterway at the lower part of the hull having its axis in the vertical mid-plane of the hull; two water-passages leading from each end of said housing or waterway symmetrically disposed with respect to said vertical mid-plane, and emerging through the hull toward the bow and stern respectively; a rotary propeller in said 15 housing having its shaft journaled at the end thereof between the two water-passages at each end, said housing having a cap at the upper side, removable for access to the pro-

25 peller, and water-gates in each of the four water-passages.

2. A vessel having a propeller housing or waterway at the bottom of the hull; water-passages leading from each end of such water-way or housing emerging through the hull below the water-line toward the bow and stern respectively; a propeller in the housing 30 operating to draw and force the water through such passages, the mouths of the water-passages being provided with horizontal grate-bars beveled or cut away on their outer edges to conform substantially with the 35 outline of the hull.

In testimony whereof I have hereunto set my hand, in the presence of two witnesses, at Chicago, Illinois, this 1st day of February, 40 1903.

T. RONSTROM.

In presence of—

CHAS. S. BURTON,
FREDK. G. FISCHER.
